UNITED STATES PATENT OFFICE.

JOHN KRENTZ AND MARTIN KRENTZ, OF WESTFIELD, WISCONSIN.

POTATO-SORTER.

1,156,786.

Specification of Letters Patent. Patented Oct. 12, 1915.

Application filed February 10, 1914. Serial No. 817,819.

To all whom it may concern:

Be it known that we, JOHN KRENTZ and MARTIN KRENTZ, citizens of the United States, residing at Westfield, in the State of Wisconsin, have invented certain new and useful Improvements in Potato-Sorters; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to vegetable sorters, and more particularly to that class of machines adapted for the sorting of potatoes.

The primary object of this invention is to provide a potato sorter adapted to be efficient, easy of operation, and cheap to manufacture.

A further object of this invention is to provide a machine of the character described designed to operate with a minimum of power and working parts, thus reducing the cost of operation and insuring efficiency of operation.

With these and other objects in view this invention consists in the peculiar arrangement and combination of the various elements of a potato sorter as hereinafter described and more particularly set forth in the appended claim.

Referring to the drawings forming a portion of this specification in which similar reference numerals designate similar parts wherever used, Figure 1 is a side elevation of the device, Fig. 2 is a central vertical section, Fig. 3 is a top view with the power platform removed, Fig. 4 is an end vertical elevation.

A plurality of base bars 4, 5, and 6 support longitudinal members 7 and 8 (only one of which is shown in the drawing). Mounted upon the longitudinal members are a number of uprights 9, 10, and 11, braced by means of cross beams 12, 13, and 14. The cross beam 14 is adapted to support the source of power for the operation of the machine, in the drawings illustrated as an internal combustion engine 15, having a fly wheel 16. The vertical members 12, 13, and 14, and the other parts of the framework are bolted together to form a rigid structure sufficient to stand strain. A lateral mem-

ber 17 is secured to the end upright 11. Between the cross beams 12 and the base bars 7 and 8 are additional supports 18 carrying a lateral bar 19. Mounted upon the member 10, 10 and this lateral member 17, is a relatively large hopper 20 having a forwardly placed opening 21 in the bottom thereof.

The supports 10, 10 are provided with eyes 22 and the supports 9, 9 with similar eyes 23. These eyes support rods 24 and 25 which are movable with the eyes and which are secured to and movably support a screen box 26 comprising an upper chamber 27 in communication with the hopper 20, and having a portion of its floor 28 cut away and a wire cloth 29 of large mesh inserted in the cut out portion. The upper chamber 27 terminates in an inclined spout 30 provided with a lip 31.

Below the box or chamber 27 is a second chamber 32, secured thereto by angle irons 33. The floor of the chamber 32 is wire cloth 34 of relatively finer mesh than the wire 29. The end of the box or chamber 32 is provided with a hopper spout 35. The spout 30 of the upper chamber 27 forms the end of the box 32.

Secured across the box 26 is a member 36 carrying a shaft 37 having a split ring bearing 38 thereon which engages an eccentric shaft 39, the purpose of which will be hereinafter described.

Carried by bearings on the members 13 and 18 are rollers 40, 41 which have an endless belt 42 the entire width of the machine, and provided with cleats 43 thereon.

A roller 44 mounted between the forward uprights 9 carries a conveyer 45 comprising a wide belt provided with cleats 46 padded with cloth or other similar material 47 to prevent bruising the potatoes. The conveyer 45 is supported at its outer high end in any suitable manner preferably by legs 48 carrying a cross beam 50 having a roller 51 thereon which engages the outer end of the conveyer belt and is supported by bearings 52 and 53.

Power is supplied to the device as follows:—The lower roller 40 is provided with a large pulley wheel 54 and the eccentric shaft 39 is similarly provided with a pulley wheel 55. The conveyer roller 44 is also provided with a large pulley wheel 56 similar to 54 and 55. A belt 57 is passed over

the fly wheel 16 and thence to the underside of the wheel 54 and upwardly over the wheel 55 to an idler pulley 58, then into engagement with wheel 56, afterward passing 5 under an idler 59 to the wheel 16, forming an endless belt.

The operation of the apparatus is as follows: The potatoes or other vegetables to be sorted are poured into the hopper 20 where 10 they fall downwardly through the opening 21 into the box 27. The gas engine 15 having its fly wheel 16 rotating in a counter clockwise direction, causes, by means of the belt 57, a clockwise rotation of the pulley 15 wheel 54 transmitting motion to the endless belt 42. Similarly the pulley wheel 55 receives a counter clockwise impulse actuating the crank eccentric 38 and the rod 37, thereby oscillating the screening box 26. The belt 20 57 imparts a counter clockwise movement to the wheel 56, thus operating the conveyer 45.

The shaking motion of the box 26 causes the potatoes to be fed to the lower inclined end of the box, the smaller potatoes falling 25 through the wire mesh screen 29 into the lower chamber 32. The large potatoes move outwardly to the spout 30, and out over the lip 31 onto the conveyer 45 which is in communication with a wagon, car, or the like, 30 which is provided to receive the first grade potatoes. As above stated, the small potatoes will fall through the mesh 29 into the lower box 32, where the larger of the smaller potatoes will be separated out in the following 35 manner. The continued shaking motion of the box causes an agitation of the potatoes whereupon the very small ones will drop through the wire mesh 34, together with all sand, dirt, grit, or the like, on to the belt 42, 40 and conveyed upwardly by the said belt to any suitable point where there may be located a refuse holder which is not illustrated in the accompanying drawings. The larger potatoes in the second box 32 are gradually 45 shaken downwardly until they reach the spout 35, when they drop through into a

receptacle 58 which is provided for the purpose.

It will thus be seen that this machine is capable of grading potatoes or other vegetables of similar size and shape into three different grades; namely the first grade which passes from the box 27 out upon the spout 30 and upon the conveyer 45; a second grade which is deposited in the receptacle 58; and a third grade which, if desired, may be separated from the refuse caught by the belt 42.

We realize that considerable variation of the details of this invention may be resorted to without departing from the spirit thereof, and it is not our intention to limit ourselves to the specific embodiment illustrated herein, but to construe the claim as broadly as the state of the prior art will permit.

What we claim as new and desire to secure by United States Letters Patent, is:—

In a vegetable sorter, the combination with a hopper, of a shaking screen below said hopper, said screen of relatively large 70 mesh, a second screen below the first mentioned screen and in communication therewith, the second screen being of smaller mesh, a downwardly and upwardly extending discharge spout on said first mentioned 75 screen and closing the lower end of the chamber between the screens, a framework, means for pivotally supporting said screens on the framework, means for shaking said screen and means for receiving the material 80 discharged from said screens.

In testimony whereof we have signed our names to this specification in the presence of subscribing witnesses.

JOHN KRENTZ.
MARTIN KRENTZ.
